UNITED STATES PATENT OFFICE.

HOWARD H. RIGGLEMAN, OF NEW LONDON, CONNECTICUT.

DRAWERS-SUPPORTER.

SPECIFICATION forming part of Letters Patent No. 602,958, dated April 26, 1898.

Application filed March 9, 1897. Serial No. 626,579. (No model.)

To all whom it may concern:

Be it known that I, HOWARD H. RIGGLEMAN, a citizen of the United States, residing at New London, in the county of New London 5 and State of Connecticut, have invented certain new and useful Improvements in Drawers-Supporters; and I do hereby declare the following to be a full, clear, and exact description of the invention, such as will enable others skilled in the art to which it appertains to make and use the same.

This invention relates to garment-supporters, and is especially designed for supporting undergarments, such as drawers.

15 The aim of the invention is to provide a clip which is adjustable or slidable upon one of the suspender-ends and which, after the suspenders have been secured to the trousers, may be slid so as to be brought into engagement with the drawers for upholding the latter in a secure and efficient manner.

25 The invention consists in a garment-supporter embodying certain novel features and details of construction, as hereinafter fully described, illustrated in the drawings, and 25 pointed out in the claims.

30 In the accompanying drawings, Figure 1 is a perspective view of the improved garment-supporter *per se*. Fig. 2 is a similar view 30 showing the supporter as applied to a suspender-end. Fig. 3 is a sectional view showing the manner in which the supporter engages the drawers. Fig. 4 shows a slight modification in the form of the supporter.

35 Similar numerals of reference designate corresponding parts in the several views.

The garment-supporter contemplated in this invention is in the form of a metal clip, the same being constructed in one piece from a 40 sheet-metal blank. A piece of metal, (indicated at 1,) which is originally of substantially rectangular shape, is deflected at one end (the upper end) when the device is in its applied position to form a V-shaped bend 45 2. At this end of the clip or supporter two apertures are formed, 3 indicating the upper aperture, and 4 the lower one, which lies close to the upper one, being separated therefrom by means of a cross web or bar 5. The apertures 3 and 4 are shown as rectangular; but

of course their shape may be varied without departing from the principle of this invention.

Extending vertically across the upper aperture 3 is a central cross bar or web 6, which is adapted to lie between the divided portions 55 7 of a suspender-end, so as to engage with the loop of the suspender-end and prevent the clip or supporter from becoming entirely displaced therefrom. This cross bar or web 6 may be dispensed with where the supporter 60 or clip is to be sold independently of the suspenders; but where the suspenders are sold equipped with the clips or supporters it is preferred to employ said cross bar or web 6 for the purpose stated. 65

The lower edge of the clip or supporter 1 is recurved, as indicated at 8, and provided with teeth or spurs 9, adapted to engage the upper edge of the drawers for supporting the same. The lower edge of the clip is recurved upon 70 that side where the suspender-end is received and so as to face the inner surface of the trousers. After the suspenders have been secured to the buttons on the trousers the clip is slid downward on the suspender-end and carried 75 inside of the trousers. The drawers are then lifted and pressed close to the inner surface of the upper band of the trousers, and the clip is then pushed against the drawers until the teeth 9 engage therewith, when, by reason of 80 the particular disposition of the curved or deflected upper end of the clip in connection with the teeth 9, the clip will be normally pressed toward the trousers, thus insuring the retention of the drawers upon the teeth of 85 the clip. In disengaging the clip may be readily disengaged from the drawers and slid upward on the suspender-ends.

It will of course be understood that the supporter or clip hereinbefore described is 90 susceptible of changes in the form, proportion, and minor details of construction, which may accordingly be resorted to without departing from the principle or sacrificing any of the advantages of the invention. 95

Having thus described the invention, what is claimed as new, and desired to be secured by Letters Patent, is—

1. A clip for the purpose described, consisting of a single piece of sheet metal hav- 100

ing one end recurved and toothed, and its opposite end apertured, the last-named end being bent in substantially V shape and the aperture therein being crossed by a bar or web, 5 substantially as and for the purpose described.

2. A clip for the purpose described, formed from a single piece of sheet metal, having one end recurved and toothed, and the opposite end apertured, a cross-bar extending across 10 said aperture, and an auxiliary cross-bar con-

nected and extending substantially at right angles to said first-mentioned cross-bar, substantially as and for the purpose described.

In testimony whereof I have signed this specification in the presence of two subscribing witnesses.

HOWARD H. RIGGLEMAN.
